US0D1062389S

(12) **United States Design Patent** (10) **Patent No.:** **US D1,062,389 S**
(45) **Date of Patent:** **** Feb. 18, 2025**

(54) **LUNCH BOX**

(71) Applicant: **Wanlu Zhou**, Shenzhen (CN)

(72) Inventor: **Wanlu Zhou**, Shenzhen (CN)

(**) Term: **15 Years**

(21) Appl. No.: **29/909,221**

(22) Filed: **Aug. 2, 2023**

(30) **Foreign Application Priority Data**

Jul. 6, 2023 (CN) 202330422696.7

(51) **LOC (15) Cl.** **09-07**

(52) **U.S. Cl.**

(57) **CLAIM**

The ornamental design for a lunch box, as shown and described.

DESCRIPTION

FIG. 1 is a front, right and top perspective view of a lunch box, showing my new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view in the open configuration thereof.

The broken lines shown in the drawings illustrate portions of the lunch box that form no part of the claimed design.

1 Claim, 9 Drawing Sheets
